UNITED STATES PATENT OFFICE

2,400,300

REGENERATIVE FURNACE

Kurt C. Gehring, Homewood, Ill., and Sebren T. Puryear, Munster, Ind., assignors to Carnegie-Illinois Steel Corporation, a corporation of New Jersey

Application January 11, 1943, Serial No. 472,032

3 Claims. (Cl. 263—44)

The present invention relates to specific structural features of improvement in open hearth regenerative furnaces of the type used in making or refining steel. More particularly, the invention is directed to a burner tunnel structure for protecting the burner of an oil or gas-fired furnace.

Heretofore the means for protecting the burner tunnel has included a structural frame with a flat cooler tank seated on the top thereof, and side cooling tanks fastened thereto. In addition, in prior constructions a series of cooling pipes are usually embedded in the brickwork at the nose of the tunnel and in both sides with a separate cooler tank supporting the burner at the inside end of the tunnel. These prior art practices are objectionable, first, because they necessitate the use of a multiplicity of pipe connections which of necessity are made in a relatively restricted area and therefore inaccessible, and cannot be readily maintained in proper operating condition. Moreover, in the old practice many special bricks must be cut to fit over and around the cooling pipes embedded in the brickwork.

One object of the present invention is to provide a cooler tunnel which combines top and side cooling legs and presents a smooth exterior surface to the brickwork on three sides and at the rear of the burner tunnel. Thus our improved cooling tunnel simplifies the laying of bricks, and exposes a relatively homogeneous mass of refractory material to the gases at the outgoing port end of the furnace. This contributes to longer life of the brickwork.

Another object of the invention is the elimination of many pipe connections formerly required so as to conserve essential materials and to cut down initial installation and maintenance costs.

A further object is to provide a cooling tunnel structure wherein a sufficient volume of cooling water in a single tank will more effectively protect the exposed brickwork than would the same volume of water in many small streams such as in the separate pipes heretofore used.

The above and other detailed features of improvement will be fully apparent from the following disclosure when read in connection with the accompanying drawings, in which:

Figure 1 is a horizontal section through one end of an open hearth furnace equipped with a burner cooling tunnel embodying the present invention.

Figure 2 is a section on line II—II thereof.

Figure 3 is a section on line III—III of Figure 1.

Figure 4 is a detail view of a water-cooled support for the inner end of the burner.

Figure 5 is an enlarged longitudinal section of

the improved burner tunnel detached from the furnace.

Figure 6 is an elevation as viewed from the left end of Figure 5.

Figure 7 is a detail view showing the water circulation for the burner support of Figure 4.

Referring in detail to the drawings, the letters A and B represent the front and back brickwork walls respectively of a conventional form of open hearth furnace having at each end a conventional end wall such as indicated at C, except that it is equipped with a built-in water-cooled tunnel of a novel design and arrangement hereinafter more fully set forth in detail. The furnace is formed with the usual air uptakes D—D which are connected by ports E—E leading to the combustion chamber F in the usual manner, which chamber communicates with the usual hearth zone of the furnace proper.

20 A burner G is provided which supplies either liquid or gaseous fuel to the combustion chamber F of the furnace. The fuel mixes in the usual manner with air heated in conventional regenerators (not shown), and the air flows through the uptakes D in the ports E to the combustion chamber F. The burner G is connected with a suitable fuel supply by pipe H in any conventional manner.

25 A particular feature of the invention herein claimed relates to the structural design and arrangement of a burner tunnel unit indicated as a whole by reference numeral T. This tunnel unit comprises an inverted inner U-shaped shell 1 and a similar outer shell 2 parallel thereto, the shells being connected together at the bottom of the structure and the space between them being closed at the inner end by an end wall 3. Thus the tunnel structure provides upright side water legs connected with the top by the curved arch passageway defined by the shells 1 and 2. At the outer end of the furnace, spaced walls 4 and 5, as best shown in Figure 5, are connected with the inner and outer walls 1 and 2, so as to provide an end water box 6.

30 Two inlet connections are provided in the end wall 4 to supply cooling water to the distributing pipes 9 and 10, which pipes have upright branches 11 and 12 which at their outer ends carry couplings 13 adapted to receive short lengths of pipe for varying the discharge point of said branches 11 and 12. The function of pipes 9 and 10 is to discharge cool water near the ends of the side water legs of the tunnel, where such water will rise and flow rearwardly, as indicated by the arrows in Figure 5, toward the water box 6. The 35 upright pipes 11 and 12 are provided to assure a

static head in the distributing pipes 9 and 10 and also to maintain an adequate supply of water near the overflow point at an effective cooling temperature. At the lower outer corner of the water box 6, outlet spuds 15 are provided which are adapted to be connected by pipes not shown, to a waste water-line. The box 6 is normally closed at the top by a detachable cover 16 which is adapted to permit of ready inspection of the water circulation in the cooling tunnel structure. Near the lower ends of the side legs of the tunnel structure, plugged spuds 17 and 18 are provided which permit of draining the tank and cleaning out any accumulated sludge or other foreign matter from time to time.

The side water legs are equipped, near their lower ends, with pipes 19 and 20, adapted to be connected with a suitable compressed air supply which is admitted periodically so as to create sufficient turbulence in the water to effect elimination of deposits from raw water. This provides efficient means for cleaning the tank without requiring the removal of the tunnel structure from its normal location in the port end of the furnace.

The end water box 6 at the outer end of the tunnel structure, as clearly shown in Figure 5, is wider at the top than at the lower portion thereof, since the upper outermost end wall 21 is spaced a substantial distance beyond the lower outer end wall 4. The upper extremity of the wall 4 extends a short distance beyond the horizontal wall 22 which connects wall 21 with wall 4, as shown, to thus form an interior baffle.

Ears 23-23 are formed on the side walls of the water box 6, and these carry fittings or lifting rings 24-24 adapted to be engaged with a crane hook so as to facilitate initial installation of the tunnel or removal when repair or replacement becomes necessary.

The tunnel passage is open to atmosphere at its outer end and substantially closed at its inner end by water-cooled member 25 of inverted U-shape, shown in Figure 4, which also serves as a support or rest for the inner end of the burner, to prevent falling or drooping thereof. The water circulation for said member 25 is shown by the arrows in Figure 7.

Having thus described a specific novel construction of burner tunnel which an actual reduction to practice has demonstrated is very desirable and efficient in practical metallurgical furnace operation, what we desire to secure by Letters Patent is defined specifically in the following claims.

We claim:

1. In a metallurgical furnace, a protective tunnel structure for a fuel burner comprising inner and outer spaced walls connected at the bottom by closure portions and at the top by arched portions so as to jointly define an inverted U-shaped tunnel structure having hollow side water legs

connected together at the top by said arched portions, a wall connected to the inner extremities of said inner and outer spaced walls and closing the inner ends of said water legs, and an outer end water box communicating with said side water legs and located beyond the outer end face of the end wall of the furnace, the structure recited defining a tunnel passageway open to atmosphere at its outer end, and a burner extending through said passageway and supported against drooping by a water-cooled member substantially closing the inner end of said tunnel passageway.

2. In a metallurgical furnace, a protective tunnel structure for a fuel burner comprising inner and outer spaced walls connected at the bottom by

closure portions and at the top by arched portions so as to jointly define an inverted U-shaped tunnel structure having hollow side water legs connected together at the top by said arched portions, a wall connected to the inner extremities of said inner and outer spaced walls and closing the inner ends of said water legs, an outer water box communicating with said side water legs located beyond the outer end of the furnace, a burner housed between the water legs of said tunnel structure, and an upright hollow water-cooled closure adjacent the inner extremity of the tunnel substantially closing the space between the side water legs and the arched portions thereof, said closure having a seat portion on which the burner rests, the passageway defined by the tunnel structure being open to atmosphere at its outer end.

3. In a metallurgical furnace, a protective tunnel structure for a fuel burner comprising inner and outer spaced walls connected at the bottom by closure portions and at the top by arched portions so as to jointly define an inverted U-shaped tunnel structure having hollow side water legs

connected together at the top by said arched portions, a wall connected to the inner extremities of said inner and outer spaced walls and closing the inner ends of said water legs, an outer water box communicating with said side water legs and located beyond the outer end of the furnace, a burner housed between the water legs of said tunnel structure, an upright hollow water-cooled burner support adjacent the inner extremity of the tunnel substantially closing the space between the side water legs and the arched portions of the tunnel, said burner support having spaced legs connected by an arched portion shaped to form a ledge on which the burner rests, and inlet and outlet coolant pipes connected with the legs of said closure member, the passageway defined by the tunnel structure being open to atmosphere at its outer end.
